STRAIGHT BAR KNITTING MACHINE

Alfred Percy Saunders, Leicester, England, assignor to Wildt and Company Limited, Leicester, England, a British company

Application August 13, 1949, Serial No. 110,060
In Great Britain September 1, 1948

14 Claims. (Cl. 66—126)

1

This invention relates to straight bar knitting machines, and has reference particularly to the mechanism incorporated in such a machine for selecting and operating the yarn carriers when producing shaped garments or parts thereof, or articles such as fully fashioned stocking blanks.

In this connection the invention has reference particularly to yarn carrier driving mechanism of the kind wherein the yarn carriers are traversible to variable extents, determined by stops, by reciprocable driving means having a constant stroke.

Heretofore, for driving the reciprocatory yarn carriers, friction devices have usually been employed, these driving devices maintaining their friction to the ends of their operating strokes. As a consequence a machine furnished with such devices is subjected to a frictional load at times when it is not required.

The primary object of the present invention is to provide an improved, compact and efficient yarn carrier driving mechanism of the kind referred to designed to enable the overall width of the machine to be reduced to a minimum, and to maintain the required variations in the extents of travel of the yarn carriers without engendering unnecessary friction against the driving mechanism at the appropriate times.

A particular aim is the provision, in a straight bar knitting machine, of a yarn carrier driving arrangement which is located remote from, and hence quite clear of, the knitting head of the machine, thereby enabling the space adjoining the head more easily to accommodate and render accessible other mechanisms.

In the improved yarn carrier driving mechanism constituting this invention, the yarn carriers are traversible through the medium of reciprocable operating members which, together with the housing in which they reciprocate, are selectively controllable, the construction and arrangement being such that whenever an operating member and its housing are selected and brought into the range of, and the operating member is acted upon by, the driving means, traverse of the corresponding yarn carrier is effected until arrested by the appropriate stop at which time the said operating member is automatically disengaged from the driving means thereby enabling the latter to reciprocate to the full extent of their constant stroke.

Thus, by reason of this construction and arrangement, whenever the driving means are free of the operating members, they are relieved of any frictional load.

2

Preferably, the operating members are mounted for movement in a path substantially at right angles to that in which the yarn carriers are traversible.

5 In a convenient embodiment of the invention, the yarn carrier selecting and driving arrangement comprises, in combination, a plurality of slides fitted with yarn carriers and mounted for reciprocation to various extents along yarn carrier bars disposed parallel to the straight needle bed, further bars fulcrumed to the yarn carrier bars and disposed substantially at right angles thereto, slides with attached operating members which are movable up and down the operating 10 bars, the slides associated with the yarn carrier bars being connected with the slides associated with the operating slide bars by reciprocable flexible members housed within the bars, and continuously reciprocable driving means 15 having a constant stroke for action on a selected operating member or members.

By a "reciprocable" flexible connecting member is meant one which is capable, when moved in a reciprocatory manner, of maintaining its form, and hence its efficacy for the intended purpose, irrespective as to whether it is pulled or pushed.

In this embodiment, the operating slide bars constitute the aforementioned "housings" for the operating members and are movable, selectively, about their fulcrum points to bring the corresponding operating members into and out of the range of the driving means according to requirements. As will be understood when an operating slide bar is turned angularly towards or away from the driving means, it moves without affecting the corresponding flexible connecting member.

40 In order that the invention may be more clearly understood and readily carried into practical effect, a specific constructional example of the improved yarn carrier selecting and driving mechanism will now be described with reference to the accompanying drawings, wherein,

45 Figure 1 is a plan view of the said mechanism.

Figure 2 is a general perspective view showing one of the yarn guides with its associated operating slide and the means for selectively operating the same,

50 Figure 3 is a detail front elevational view of one of the yarn carrier slides, the corresponding operating member slide and the flexible member connecting the two,

55 Figure 4 is a detail transverse sectional view taken on the line IV—IV of Figure 2,

Figure 5 is a further detail transverse sectional view taken on the line V—V of Figure 2.

Figure 6 is a fragmentary front view illustrating the fulcrum between one of the yarn carrier bars and the corresponding operating slide bar.

Figure 7 is a vertical sectional view of the continuously reciprocable driving means shown in relation to one of the operating slide driving members.

Figures 8–14 inclusive are diagrams illustrating successive stages in the actuation of one of the operating slide driving members by the continuously reciprocable driving means.

Figure 15 is an elevational view of the connections through which the continuously reciprocable driving means are driven from the main cam shaft of the machine, and

Figure 16 is a fragmentary front elevational view of the chain included in the continuously reciprocable driving means showing the connection of this chain to the slur cam bracket as will be hereinafter described.

Like parts are designated by similar reference characters throughout the drawings.

In Figure 1 the side frames of the machine are indicated at 1 and 2. Upon the upper ends of these frames are attached housings 3 and 4 in which are mounted horizontal yarn carrier bars 5 arranged one behind the other. Seven of these bars are shown although, of course, this number may be varied according to requirements. Each of the bars 5 carries a plate 6 to which a yarn carrier 7 is attached, and this plate is traversible back and forth between fixed outside stops 8 and 9. Fulcrumed at 10 to the left-hand ends of the yarn carrier bars 5 are slide bars 11 which are selectively operable from the main control drum 12 of the machine, through the medium of cams 13 on the said drum, fulcrumed operating levers 14 and Bowden cables 15.

At 27 is represented a chain included in the continuously reciprocable driving means.

The yarn carrier selecting and driving mechanism will now be described in detail. As will be seen, the mechanism includes a plurality of T-section slides 17 to the fronts of which the yarn carrier plates 6 are secured by means of screws 18, these slides being mounted for reciprocation to various extents within the bars 5. In this connection, each bar 5 has formed therein a longitudinal recess 19 to receive the corresponding slide 17 and the latter is retained in position within the recess by vertically spaced guide rails 20 riveted to the front of the said bar. Two fixed outside stops, i.e., right-hand stop 8 and a left-hand stop 9 are screwed in position upon the front of each yarn carrier bar 5. Each of the substantially vertical slide bars 11 is connected at its upper end to the left-hand end of the corresponding yarn carrier bar 5 by a fulcrum screw 10. This screw passes through a clearance hole drilled in a bearing piece 21 welded to the slide bar 11 and is screwed into a tapped hole in the bar 5. Each bar 11 is longitudinally recessed at 22 (see Figure 2) to receive a vertically movable T-section slide 23 which has attached thereto, by means of screws 24, an operating member 25. The slide 23 is retained in position within the recess 22 by means of suitably spaced guide rails 26 riveted to the front of the bar 11. As shown more clearly in Figure 3, the left-hand end of each of the horizontal slides 17 is connected to the upper end of the corresponding vertical slide 23 by means of a length of chain 27 of the roller

type. The rollers 28 (Figure 4) are engaged at opposite sides by the pairs of guide rails 20 and 26 which latter as will be appreciated, provide between them, and together with the recesses 19 and 22, T-shaped slots 29 and 30 respectively. The left-hand end of the T-shaped slot 29 in each yarn carrier bar 5 is extended at 29a (see Figure 6) in a curve which is concentric with respect to the axis of the fulcrum screw 10, thereby enabling the length of chain 27 properly to perform its function of transmitting motion from the operating member 25 to the yarn carrier 7, this function being in no wise adversely affected by movement of the operating slide bar 11 about its fulcrum 10—when selected for co-operation with the continuously reciprocable driving means presently to be described. The inner face of the right-hand outside fixed stop 8 on each bar 5 is recessed at 8a (see Figure 2) to clear the corresponding slide 17 at such times as the relevant yarn carrier plate 6 is moved into contact with the said stop. In a similar way, the inner face of the left-hand outside fixed stop 9 is recessed at 9a to clear the chain 27.

The movable outside stops are indicated at 31 and 32 in each of Figures 1 and 2.

To ensure precise positioning of the plates 6 and the yarn carriers 7 when contacting their stops, adjustable damping devices are fitted both to the plates 6 and to the operating members 25 to act as rebound checks.

Preferably, the damping devices operate by frictional contact with the bars 5 and 11. One such damping device is depicted in Figures 2 and 35, 35; as will be seen, it comprises a leather pad 33 mounted in a holder 34 which is mounted in a slide-piece 35 attached by screws 36 to the back of the plate 6. Compression springs 37, the pressure of which is variable by screws 38, are interposed between the holder 34 and the slide-piece 35. A damping device operating by frictional contact upon the bar 11 is shown in Figures 2 and 7 and consists of a leather pad 39 fixed in a holder 40 which latter is spigoted at 41 into a boss 42 integral with the operating member 25. A compression spring 43 is housed within the boss 42 and arranged to exert a light pressure upon the holder 40 and, through the medium of the leather pad 39, upon the bar 11.

Each of the operating members 25 is furnished with a pair of oppositely disposed yieldable dogs 44 and 45. These two dogs are mounted slidably in transverse slots 46 and 47 formed in the back of the operating member 25 and are retained in the said member partly by the bar 11 and partly by a cover plate 48 serving also to carry a spring 49 arranged to act upon positioning pins 50 fixed in the tail ends of the dogs. The spring 49 is mounted centrally between its ends upon a screw 51 screwed both into the cover plate 48 and into the operating member 25. Each of the pins 50 is located in a recess 52 formed in one end of the cover plate 48, the ends of this recess limiting the movement of the corresponding dog in either direction. Normally, of course, the dogs 44 and 45 are held by the spring 49 in their projected positions—determined by the inner ends of the recesses 52. The pairs of yieldable dogs 44 and 45 are for co-operation selectively with a corresponding series of single yieldable driving elements 53 pivotally mounted at 54 in slots 55 in a cut bar 56 attached to a common carrier 57. The carrier 57 is mounted upon a vertical slide rod 58 for movement up and down, adjacent to the operating slide bars 11, at the left-hand side

of the machine. The carrier 57 is guided, during its vertical reciprocatory movement, by a guide bar 59. In this connection there are provided retaining bars 60 and a retaining plate 61 (see Figures 15 and 16) attached respectively to the front and the back of the carrier 57 and arranged to engage opposite sides of the guide bar 59. Each single yieldable driving element 53 is controlled by a pair of axially opposed spring-loaded plungers 62 which normally function to maintain the said element in the horizontal driving position indicated in Figures 7, 8, 9, 11, 12, 13, 14 and 16. The plungers 62 are of a greater width than the slots 55 in which the associated yieldable driving elements 53 are pivotally mounted, so that downward movement of the upper plungers, effected by springs 63, is limited by contact with the top face of the cut bar 56, whilst the upper movement of the lower plungers, effected by springs 64, is limited by contact with the underside of the bar 56. Consequently, whenever a yieldable driving element 53 is brought into contact with a dog 44, the said element will be deflected downwardly against the action of the corresponding upper spring 63, whereas movement of the element into contact with the opposed dog 45 will cause the element to be deflected upwardly against the action of the relevant lower spring 64, the element in either event being automatically restored to its mid, i. e. normal horizontal driving, position when permitted to do so. The ends of the springs 63 and 64 remote from the operative portions of the plungers 62 bear upon screwed bushes 65 by appropriate turning movement of which the pressure exerted by the springs can be varied, according to requirements. The screwed bushes 65 are formed with enlarged heads 66 which are peripherally notched for co-operation with index plates 67 secured on the carrier 57 by screws 68. To enable it to be vertically reciprocated the carrier 57 is secured to a portion 69a of a continuously reciprocable endless chain 69 mounted upon chain sprockets 70 at the back of the machine. As shown in Figure 15, the chain 69 derives its motion from an oscillatory segment gear 71, through the medium of a spur pinion 72 to which is attached a bevel gear 73, and an intermeshing bevel pinion 74 in turn secured to the appropriate chain sprocket 70. The oscillatory segment gear 71, which is fulcrumed at 75, is furnished with spaced rollers 76 and 77 arranged to be acted upon by small and large edge cams 78 and 79 respectively which cams are relatively disposed in the manner shown and both secured by a screw 80 to a spur gear 81. This gear is arranged in mesh with a driving pinion 82 on the main cam shaft of the machine. The ratio of the driving pinion 82 to the gear 81 is 2/1. The rollers 76 and 77 are arranged in different planes to correspond with the planes of the cams 78 and 79. The chain 69 is also used to drive a bracket 83 carrying the slur cam 84, this bracket being attached to the chain by means of a plate 85 secured by screws 86. The portion 69b of the chain 69 to which the slur cam bracket 83 is attached extends parallel to the yarn carrier bars 5, whilst the portion 69a of the said chain to which the carrier 57 is attached extends parallel to the slide rod 58 and the guide bar 59. In this way accuracy of the positioning of the yarn carriers 7 in relation to the slur cam 84, in both directions of knitting, is ensured.

Referring again to the means for selecting the operating slide bars 11 to bring the corresponding

operating members 25 into the range of the relevant yieldable driving elements, it should be mentioned that the control drum 12 is fitted with a rack wheel 87 (see Figure 1), adapted to be racked round by conventional racking means (not shown). The drum 12 is racked to effect selection of a desired operating slide bar 11 irrespective of which end of its stroke the corresponding operating member 25 has been left at a previous selection.

Referring to Figure 8, the operating slide bar 11, a fragmentary portion of which is depicted therein, has been selected to bring the corresponding operating member 25, together with its two projected yieldable dogs 44 and 45, into the range of the relevant yieldable driving element 53. The said element 53 is in the course of being moved upwards and is about to act on the lower dog 44. In Figure 9, the element 53 is shown in contact with the dog 44, these parts remaining in the same relative position until the appropriate portion of the plate 6 of the corresponding yarn carrier 7 comes into contact either with the movable outside stop 32 or the fixed outside stop 8, as the case may be. When this happens, the operating member 25 is arrested as a consequence of which the driving element 53 is turned downwards on its pivot 54 against the action of the plunger 62 controlled by the spring 63 to enable it to be disengaged from the dog 44. In this connection it will be noted that to expedite disengagement of the element 53 from the dog 44, the said element is formed with an integral lug 53a adapted for action on the vertical face of the dog 44 for the purpose of pushing the latter inwards against the action of the spring 49. Having been disengaged from the dog 44 and returned under the action of the plunger 62 and spring 63 into its normal horizontal driving position, the yieldable element 53 continues its upward movement, see Figure 11, until brought into contact with a sloping cam face 45a on the dog 45 whereupon the latter is depressed against the action of the spring 49, thereby permitting the element 53 to pass by the dog 45, in the manner depicted in Figure 12, and complete its upward stroke. In Figure 13, the yieldable element 53 is shown in the course of making a reverse, i. e. downward, stroke to make contact with the dog 45 (Figure 14) and drive the operating member 25 downwards until the aforesaid plate 6 is brought into contact with the movable outside stop 31 or the fixed outside stop 9. At this stage, the element 53 yields upwardly against the action of the plunger 62 controlled by the spring 64 and is disengaged from the dog 45. To expedite this disengagement, the element 53 is formed with a lug 53b adapted for engagement with the dog 45 suchwise as momentarily to depress the latter.

What I claim then is:

1. In a straight bar knitting machine, yarn carrier driving mechanism comprising, in combination, reciprocatory yarn carriers, stops for determining the extents to which the said yarn carriers are traversible, reciprocable operating members, spring-controlled dogs fitted in the said operating members, bars in which the operating members reciprocate, means for transmitting motion between the operating members and the yarn carriers, continuously reciprocable driving means having a constant stroke, and including yieldable elements for co-operation with the aforesaid dogs, and means for selectively moving the operating members and their bars into and out of the

range of the said driving means, the construction and arrangement being such that whenever an operating member and its bars are selected and brought into the range of the driving means the relevant yieldable driving element acts upon the dogs of the appropriate pair alternately and so effects traverses of the corresponding yarn carrier in opposite directions and the extents of which are determined by arrest of the yarn carrier by the appropriate stops at which times the said driving element yields and disengages the operating member from the driving means, thereby enabling the latter to reciprocate to the full extent of their constant stroke.

2. In a straight bar knitting machine yarn carrier driving mechanism comprising, in combination, reciprocating yarn carriers, stops for determining the extents to which the said yarn carriers are traversible, reciprocable operating members mounted for movement in a path at right angles to that in which the yarn carriers are traversible, spring-controlled dogs fitted in the said operating members and normally projected from the latter under the spring action, slides to which the yarn carriers are fitted, further slides serving to carry the operating members, flexible members for connecting and transmitting motion between the two sets of slides, the said flexible connecting members functioning both when pulled or pushed, bars in which the slides carrying the operating members reciprocate, continuously reciprocable driving means having a constant stroke and including yieldable elements for co-operation with the aforesaid dogs, and means for selectively moving the operating members and their slides and bars into and out of the range of the said driving means, the construction and arrangement being such that whenever an operating member and its bar are selected and brought into the range of the driving means the relevant yieldable driving element acts upon the dogs of the appropriate pair alternately and so effects traverses of the corresponding yarn carrier in opposite directions and the extents of which are determined by arrest of the yarn carrier by the appropriate stops at which times the said driving element yields and disengages the operating member from the driving means, thereby enabling the latter to reciprocate to the full extent of their constant stroke.

3. In a straight bar knitting machine, in combination, a straight needle bed, yarn carriers for supplying yarns to needles in said bed, a plurality of reciprocable slides to which the yarn carriers are fitted, yarn carrier bars upon which the said slides are mounted for reciprocation, stops for determining the extents to which the yarn carriers reciprocate, further bars articulated to the yarn carrier bars, slides movable along the said further bars, operating members attached to said last mentioned slides, a pair of spaced and oppositely directed spring-controlled dogs on each operating member, reciprocable flexible members for connecting the slides on the yarn carrier bars with the slides on the further bars, the said flexible connecting members being housed within the bars and capable of being both pulled and pushed, continuously reciprocable driving means having a constant stroke and furnished with yieldably mounted elements for co-operation with the pairs of spring-controlled dogs on the operating members, and means for selectively moving the aforesaid further bars so as to bring desired operating members into and out of the range of the driving means, whereby, whenever either

dog on a selected operating member is acted upon by a yieldable element included in the driving means, traverse of the corresponding yarn carrier is effected until arrested by the appropriate stop at which time the said operating member is automatically disengaged from the driving means thereby enabling the latter to reciprocate to the full extent of their constant stroke.

4. In a straight bar knitting machine, in combination, a horizontally disposed straight needle bed, yarn carriers for supplying yarns to needles in said bed, a plurality of reciprocable slides to which the yarn carriers are fitted, yarn carrier bars disposed parallel to the straight needle bed and upon which the said slides are mounted for reciprocation, stops for determining the extents to which the yarn carriers reciprocate, further bars which are fulcrumed to the yarn carrier bars and are disposed vertically, slides movable up and down the vertical bars, operating members attached to said last mentioned slides, a pair of spaced and oppositely directed spring-controlled dogs on each operating member, which dogs are normally projected from the operating member under the spring action, reciprocable flexible members for connecting the slides on the yarn carrier bars with the slides on the vertical bars, the said flexible members being housed within the bars and capable of being both pulled and pushed, continuously reciprocable driving means having a constant stroke and furnished with yieldably mounted elements for co-operation with the pairs of spring-controlled dogs on the operating members, and means for selectively moving the vertical bars so as to bring desired operating members into and out of the range of the driving means, the construction and arrangement being such that when an operating member together with its slide and vertical carrier bar are selected to bring the said operating member into the range of the driving means, the corresponding yieldable driving element will first act on one of the appropriate pair of dogs to move the operating member in one direction until the corresponding yarn carrier contacts the appropriate stop and arrests the operating member whereupon the said element will yield and pass the engaged dog, continue its movement and depress and idly pass by the other dog, and then, upon the next stroke of the driving means, will act on the previously depressed dog to move the operating member in the reverse direction, again until arrested by reason of the aforesaid yarn carrier contacting another stop at the opposite end of its traverse, at which time the driving element again yields to enable it to pass the last mentioned dog and, in continuing its stroke, depresses and passes the first mentioned dog.

5. Yarn carrier driving mechanism according to claim 2, wherein the flexible connecting members consist of lengths of chain.

6. In a straight bar knitting machine, in combination, a horizontally disposed straight needle bed, yarn carriers for supplying yarns to needles in said bed, a plurality of reciprocable slides to which the yarn carriers are fitted, yarn carrier bars disposed parallel to the straight needle bed and upon which the said slides are mounted for reciprocation, the said bars including guide rails so spaced as to provide slots between them, stops for determining the extents to which the yarn carriers reciprocate, further bars which are fulcrumed to the yarn carrier bars and are disposed vertically, these vertical bars also including guide rails spaced to provide slots, slides

movable up and down the vertical bars, operating members attached to said last mentioned slides, a pair of spaced and oppositely directed spring-controlled dogs on each operating member which dogs are normally projected from the operating member, lengths of chain of the roller type for connecting the slides on the yarn carrier bars with the slides on the vertical bars, the rollers of the chain being engaged at opposite sides by the guide rails, continuously reciprocable driving means having a constant stroke and furnished with yieldably mounted elements for co-operation with the pairs of spring-controlled dogs on the operating members, and means for selectively moving the aforesaid further bars so as to bring desired operating members into and out of the range of the driving means, whereby, whenever either dog on a selected operating member is acted upon by a yieldable element included in the driving means, traverse of the corresponding yarn carrier is effected until arrested by the appropriate stop at which time the said operating member is automatically disengaged from the driving means thereby enabling the latter to reciprocate to the full extent of their constant stroke.

7. A combination according to claim 6, wherein the portions of the said slots adjoining the fulcrum points of the vertical bars are concentric with respect to the said points, thereby enabling the lengths of chain properly to perform their function of transmitting motion from the operating members to the yarn carriers, this function not being adversely affected by movements of the operating slide bars about their fulcrums when selected to bring about co-operation of the corresponding operating members with the driving means.

8. In a straight bar knitting machine, in combination, a straight needle bed, yarn carriers for supplying yarns to needles in said bed, a plurality of reciprocable slides to which the yarn carriers are fitted, yarn carrier bars upon which the said slides are mounted for reciprocation, stops for determining the extents to which the yarn carriers reciprocate, further bars articulated to the yarn carrier bars, slides movable along the said further bars, operating members attached to said last mentioned slides, a pair of spaced and oppositely directed spring-controlled dogs on each operating member, reciprocable flexible members for connecting the slides on the yarn carrier bars with the slides on the further bars, the said flexible connecting members being housed within the bars and capable of being both pulled and pushed, continuously reciprocable driving means having a constant stroke and furnished with yieldably mounted elements for co-operation with the pairs of spring-controlled dogs on the operating members, means for selectively moving the aforesaid further bars so as to bring desired operating members into and out of the range of the driving means, whereby, whenever either dog on a selected operating member is acted upon by a yieldable element included in the driving means, traverse of the corresponding yarn carrier is effected until arrested by the appropriate stop at which time the said operating member is automatically disengaged from the driving means thereby enabling the latter to reciprocate to the full extent of their constant stroke, and adjustable damping devices which are fitted both to the yarn carriers and to the operating members to act as rebound checks for the purpose of ensuring precise positioning of the yarn carriers when contacting their stops.

9. In a straight bar knitting machine, in combination, a horizontally disposed straight needle bed, yarn carriers for supplying yarns to needles in said bed, a plurality of reciprocable slides to which the yarn carriers are fitted, yarn carrier bars disposed parallel to the straight needle bed and upon which the said slides are mounted for reciprocation, stops for determining the extents to which the yarn carriers reciprocate, further bars which are fulcrumed to the yarn carrier bars and are disposed vertically, slides movable up and down the vertical bars, operating members attached to said last mentioned slides, a pair of spaced and oppositely directed spring-controlled dogs on each operating member, which dogs are normally projected from the operating member under the spring action, reciprocable flexible members for connecting the slides on the yarn carrier bars with the slides on the vertical bars, the said flexible members being housed within the bars and capable of being both pulled and pushed, continuously reciprocable driving means having a constant stroke and furnished with yieldably mounted elements for cooperation with the pairs of spring-controlled dogs on the operating members, a main control drum having studs thereon, a series of selector levers, one to each vertical bar, adapted for engagement by studs on the drum, and links serving to connect the said levers directly to the vertical bars, the construction and arrangement being such that whenever an operating member and its slide and vertical carrier bar are selected and brought into the range of the driving means the relevant yieldable driving element acts upon the dogs of the appropriate pair alternately and so effects traverses of the corresponding yarn carrier in the opposite directions and the extents of which are determined by arrest of the yarn carrier by the appropriate stops at which times the said driving element yields and disengages the operating member from the driving means, thereby enabling the latter to reciprocate to the full extent of their constant stroke.
10. A combination according to claim 9, wherein in the main control drum is racked to effect selection of a desired vertical bar irrespective of which end of its stroke the corresponding operating member has been left at a previous selection.
11. In a straight bar knitting machine, in combination, a horizontally disposed straight needle bed, yarn carriers for supplying yarns to needles in said bed, a plurality of reciprocable slides to which the yarn carriers are fitted, yarn carrier bars disposed parallel to the straight needle bed and upon which the said slides are mounted for reciprocation, stops for determining the extents to which the yarn carriers reciprocate, further bars which are fulcrumed to the yarn carrier bars and are disposed vertically, slides movable up and down the vertical bars, operating members attached to said last mentioned slides, a pair of spaced and oppositely directed spring-controlled dogs on each operating member, which dogs are normally projected from the operating member under the spring action, reciprocable flexible members for connecting the slides on the yarn carrier bars with the slides on the vertical bars, the said flexible members being housed within the bars and capable of being both pulled and pushed, continuously reciprocable driving means having a constant stroke and furnished with yieldably mounted elements for co-operation with the pairs of spring-controlled dogs on

11

the operating members, the said driving means being embodied in a unit including a carrier, a driving chain to which the said carrier is attached, an oscillatory gear for reciprocating the chain, means for guiding the carrier during movements thereof up and down at one side of the machine, and means for selectively moving the vertical bars so as to bring desired operating members into and out of the range of the driving means, the construction and arrangement being such that when an operating member together with its slide and vertical carrier bar are selected to bring the said operating member into the range of the driving means, the corresponding yieldable driving element will first act on one of the appropriate pair of dogs to move the operating member in one direction until the corresponding yarn carrier contacts the appropriate stop and arrests the operating member whereupon the said element will yield and pass the engaged dog, continue its movement and depress and idly pass by the other dog, and then, upon the next stroke of the driving means, will act on the previously depressed dog to move the operating member in the reverse direction, again until arrested by reason of the aforesaid yarn carrier contacting another stop at the opposite end of its traverse, at which time the driving element again yields to enable it to pass the last mentioned dog and, in continuing its stroke, depresses and passes the first mentioned dog.

12. A combination according to claim 11, wherein the chain is of endless form and, in addition to driving the carrier furnished with the yieldable driving elements, is fitted with a bracket supporting the slur cam of the machine.

13. In a straight bar knitting machine, in combination, a horizontally disposed straight needle bed, yarn carriers for supplying yarns to needles in said bed, a plurality of reciprocable slides to which the yarn carriers are fitted, yarn carrier bars disposed parallel to the straight needle bed and upon which the said slides are mounted for reciprocation, stops for determining the extents to which the yarn carriers reciprocate, further bars which are fulcrumed to the yarn carrier bars and are disposed vertically, slides movable up and down the vertical bars, operating members attached to said last mentioned slides, a pair of spaced and oppositely directed spring-controlled dogs on each operating member, which dogs are normally projected from the operating member under the spring action, reciprocable flexible members for connecting the slides on the yarn carrier bars with the slides on the vertical bars, the said flexible members being housed within the bars and capable of being both pulled and pushed, continuously reciprocable driving means having a constant stroke and furnished with yieldably mounted elements for co-operation with the pairs of spring-controlled dogs on the operating members, the said driving means being embodied in a unit including a carrier, a driving chain of endless form to which the said carrier is attached, an oscillatory gear for reciprocating the said chain, means for guiding the carrier during movements thereof up and down at one side of the machine, sprockets for guiding the chain so that a portion thereof extends parallel to the yarn carrier bars whilst the portion to which the carrier is attached extends parallel to the guiding means for the carrier, a bracket attached to the portion of the chain extending parallel to the yarn carrier bars, a slur cam fixed to the said bracket, and means for

selectively moving the vertical bars so as to bring desired operating members into and out of the range of the driving means, the construction and arrangement being such that when an operating member together with its slide and vertical carrier bar are selected to bring the said operating member into the range of the driving means, the corresponding yieldable driving element will first act on one of the appropriate pair of dogs to move the operating member in one direction until the corresponding yarn carrier contacts the appropriate stop and arrests the operating member whereupon the said element will yield and pass the engaged dog, continue its movement and depress and idly pass by the other dog, and then, upon the next stroke of the driving means, will act on the previously depressed dog to move the operating member in the reverse direction, again until arrested by reason of the aforesaid yarn carrier contacting another stop at the opposite end of its traverse, at which time the driving element again yields to enable it to pass the last mentioned dog and, in continuing its stroke, depresses and passes the first mentioned dog.

14. In a straight bar knitting machine, in combination, a horizontally disposed straight needle bed, yarn carriers for supplying yarns to needles in said bed, a plurality of reciprocable slides to which the yarn carriers are fitted, yarn carrier bars disposed parallel to the straight needle bed and upon which the said slides are mounted for reciprocation, stops for determining the extents to which the yarn carriers reciprocate, further bars which are fulcrumed to the yarn carrier bars and are disposed vertically, slides movable up and down the vertical bars, operating members attached to said last mentioned slides, a pair of spaced and oppositely directed spring-controlled dogs on each operating member, which dogs are normally projected from the operating member under the spring action, reciprocable flexible members for connecting the slides on the yarn carrier bars with the slides on the vertical bars, the said flexible members being housed within the bars and capable of being both pulled and pushed, a driving chain, sprockets for guiding the said chain, an oscillatory gear for continuously reciprocating the chain, a bracket attached to the chain, a slotted member supported by the bracket, yieldable driving elements which are pivotally mounted in slots in the said member and are formed with tails, the said yieldable elements being adapted for cooperation with the pairs of spring-controlled dogs on the operating members, spring-loaded plungers are arranged to act upon opposite sides of the tails of the yieldable elements for the purpose of normally holding the latter in a mid position, and means for selectively moving the vertical bars so as to bring desired operating members into and out of the range of the driving means, the construction and arrangement being such that when an operating member together with its slide and vertical carrier bar are selected to bring the said operating member into the range of the driving means, the corresponding yieldable driving element will first act on one of the appropriate pair of dogs to move the operating member in one direction until the corresponding yarn carrier contacts the appropriate stop and arrests the operating member whereupon the said element will yield and pass the engaged dog, continue its movement and depress and idly pass by the other dog, and then, upon the next stroke of the driving means, will act on the previously depressed

dog to move the operating member in the reverse direction, again until arrested by reason of the aforesaid yarn carrier contacting another stop at the opposite end of its traverse, at which time the driving element again yields to enable it to pass the last mentioned dog and, in continuing its stroke depresses and passes the first mentioned dog.

ALFRED PERCY SAUNDERS. 10
